CLAIM

The ornamental design for a case for containers, as shown and described.

DESCRIPTION

FIG. 1 is a top plan view of a case for containers showing my new design;

FIG. 2 is a bottom plan view thereof;

FIG. 3 is a front elevational view thereof; the rear elevational view being a mirror image thereof;

FIG. 4 is a left side elevational view thereof; the right

side elevational view being a mirror image thereof; and,

FIG. 5 is a cross-sectional view taken along line 5—5 of

FIG. 1.
